UNITED STATES PATENT OFFICE.

HENRY J. GAGNON, OF COHOES, NEW YORK.

MULTIPLE BLOW-OUT FUSE.

1,281,553.

Specification of Letters Patent. Patented Oct. 15, 1918.

Application filed November 22, 1917. Serial No. 203,387.

To all whom it may concern:

Be it known that I, HENRY J. GAGNON, a citizen of the United States, residing at Cohoes, in the county of Albany and State 5 of New York, have invented certain new and useful Improvements in Multiple Blow-Out Fuses, of which the following is a specification.

The invention has for an object to effect 10 improvements in the construction of multiple blow-out fuses, of that type in which a rotating element is employed adapted to bring one fuse after another into circuit without requiring removal of the fuse casing 15 or introduction of new parts, until the full number of fuses in the appliance has been exhausted. An important aim of the invention is to give an appliance of this character which will be largely held in assembled relation by the fuse elements themselves, and which may be quickly taken apart for renewal of the fuse elements when required. A further important purpose of the invention 20 is to give a simple means for indicating when a fuse has been blown, without exposing the fuse to view, but maintaining it securely inclosed. Another purpose is to give a cheap construction in the elements thereof attained by a novel structural form in certain parts and in the operative relation of 25 the several parts. It is an important purpose to obviate the necessity for removal of the casing or its terminals from the binding post of a switch box or from the clips of a 30 fuse block.

Additional objects, advantages and features of invention will appear from the construction, arrangement and combination of parts hereinafter set forth and shown in the 40 drawings, wherein,

Figure 1 is a perspective view of the device constructed in accordance with my invention.

Fig. 2 is a similar view of the porcelain 45 core element,

Fig. 3 is a longitudinal sectional view of the device,

Fig. 4 is a cross section of the fuse assembled showing the blow-out indicator.

Fig. 5 is a detail of the terminal block in 50 the fuse.

Fig. 6 is a plan of the blank for the fuse proper.

There is illustrated a fuse comprising a cylindrical tubular casing 10, of a suitable insulating material, notched at one end as at 55 11 to receive radial lugs 12 of a terminal block 13, in the form of a centrally apertured disk having a plurality of parallel terminal pin lugs 15 extended from one side 60 thereof in concentric spaced relation. Within the casing 10 there is a porcelain core element 16, having five V-shaped channels 17 extended longitudinally therein, and separated from each other by narrow wall portions 18, these channels stopping short of the 65 ends of the core, through the ends of which registered openings 19 are formed. The pin lugs 15 are adapted to engage snugly in the apertures 19 at one end of the core, and to 70 project a short distance into respective grooves 17. One end of the core is suitably recessed to snugly receive a nut 20, concentrically, the disk 13 being positioned over the nut and apertured to register with the 75 opening in the nut. A core head 21 is provided of cylindrical form having a diameter similar to that of the core 16, this head being provided with openings 22, therein, corresponding in number and spacing to the openings 19, and adapted to register therewith, the openings 22 in the head being slightly enlarged at their outer ends, so as to receive 80 headed pins 24, having slightly recessed heads adapted to lie within the enlarged end 85 of the passages through the core head, slightly below, or within the end surface of the head, these pins being of a length to project into corresponding openings 19 and adjacent grooves 17 of the core, when the head 90 is brought into close relation with one end of the core. At its inner side the head 21 is recessed to hold a nut 25, as shown. The casing is of a length equaling the length of 95 the core, its head, and the disk 13, when assembled as indicated, and fitted on each end of the core and casing, there are terminal caps 27 and 28, which may be stamped from suitable sheet material, being provided with cylindrical flange portions adapted to fit 100 snugly around the respective ends of the casing 10. The cap 27 is formed with an ear 29, or other suitable terminal element for engagement with a fuse block clip or other fastening, fixed in rigid relation to the cap, 105 a central aperture being formed through the

cap to receive an assembly screw 29', the cap 27 being engaged over the end of the casing with which the disk 13 is engaged, the screw 29 being presented through the disk 5 and engaged with the nut 20, while the disk 13 is disposed over this nut. The cap 28 is provided with an ear 30, similar to the one 29 at its outer part, having an inner part suitably secured upon the cap at one part, 10 but having a curved tongue 31, as nearly concentric with the axis of the cap as may be, this tongue being formed integrally with the ear 30, which has a base portion bent with the tongue 31 at right angles to its outer part and secured against the cap 28. Upon the extremity of the tongue 31 a contact lug 32 is formed, presented through a suitable opening in the cap, and located at such a distance from the axis of the cap as 20 to register with the series of openings 23 in the core head when the device is assembled. The cap is also centrally apertured to receive an assembly screw 33, for engagement therethrough, through the head 21, and 25 with the nut 25 at the inner side thereof.

The fuses 41 for use in this device comprise I-shaped blanks of fusible metal which may be readily stamped out, these fuses being bent upon a longitudinal medial line to 30 present their opposite halves at an angle to each other to permit the fuses to lie snugly in the bottoms of the grooves 17 of the core 16.

The device is assembled by adjusting the 35 lugs 15 on the disk 13 in respective openings 19 of the core at the end with the nut 20, the disk 13 being adjusted closely against the end of the core. Fuses are then introduced in the grooves, one end of each being 40 disposed under the exposed end of the lug 15 in the groove thereadjacent, and soldered welded, or otherwise secured to form a good electrical contact and prevent withdrawal of the lugs through the end of the core. The 45 pins 24 are then adjusted in the core head, and their projecting ends inserted through the openings 19 at the end of the core opposite the lugs 15, the ends of the pins thereby being positioned over the unsecured end of the fuses. The fuses are then secured to the 50 ends of these pins with the same means employed at the opposite end of the fuses, it being understood that the nut 25 has been positioned in the recessed inner side of the head. A filling of powdered asbestos or 55 other suitable material to prevent arcing in case a fuse is blown out is then introduced in the grooves of the core over and around the fuses, and this material may be retained 60 by pasting a piece of paper or other fabric 34 around the core, securing it upon the edges of the wall portions 18, and upon the cylindrical end portions of the core. The casing 10 is then adjusted around the core

with the lugs 12 engaged in the notches 11, 65 after which the cap 27 may be adjusted over the disk 13 and adjacent portion of the casing and the screw 29 engaged with the nut 20, whereby the cap 27 is clamped in position upon the end of the core. The cap 28 70 is then adjusted upon the opposite end of the device, the contact 32 being adjusted upon one of the pins 24 and the screw 33 then engaged through the cap and with the nut 25, whereby the cap is held in place. 75 Longitudinally spaced pairs of apertures 37 are formed through the casing 10 centrally over respective grooves, and through these apertures are inserted the ends of easily fusible elements 38, contacting with the fuses adjacent opposite ends, so that in case a fuse is blown out, the respective fusible element 38 will also be fused, their medial portions exteriorly of the casing being extremely small and preferably so shaped or composed 80 as to fuse with a minimum of flagration. Over these elements 38 and suitably secured upon the casing, there is a paper or other covering 39, which may have printed thereon over the respective grooves, ordinal numbers 90 and any suitable data relative to the load capacity and current capacity of the fuses.

In use, the fuses being made in the proper length, and the clips of the proper form for engagement with the fuse blocks, when the 95 device is positioned therein, the ear 29 may be adjusted in alignment with the ear 30 by loosening the screw 29', or they may be given positions in different planes having an angular relation, if necessary. It may be 100 found desirable to turn the fuse block so that the lug 32 will bear upon the porcelain head 22 between the pins 24, if desired, in which case no current would pass through the device. In that way, the appliance may be 105 used as a switch element or cut-out although with the present construction its use in that manner is not recommended with high voltages. When the parts are in proper relation, the device may be readily adjusted upon the 110 fuse clips, or between the binding posts. It is desirable that the device be adjusted with the printed wrapper on the casing disposed with number 1 at the outer side, and to more positively indicate the position in which the 115 index number should be placed, the cap element at one end of the device may have a small point marked thereon as at 40, to serve as an index pointer. In case of trouble upon the line resulting in failure of current to 120 pass, it may be determined whether a fuse has been blown by pressing the finger upon the small fuse wire under the wrapper in line with the index pointer of the device, and if it is possible to press the wrapper down 125 flat against the casing or if notable change of form is observable in the small fuse, it will be understood that it has been blown.

On the other hand, should the small outer fuse be in its original form, it may be understood that the fuse within the casing is intact. When a fuse is discovered to be blown, the screw 29 may be slightly loosened, as well as the screw 33, after which the casing may be turned to adjust a new fuse in place. When number 5 fuse has been blown, it will be understood that there are no more 10 fuse in the device for use. The device may of course be made to accommodate a greater or lesser number of fuses than shown in the particular embodiment presented in this application, as will be understood.

15. What is claimed:

1. In a multiple fuse device, a core having a plurality of longitudinal grooves therein, pin elements projecting thereinto from each end of the core, a fuse connected 20 between each two opposed pins, and means to hold the pins against removal from the core.

2. A multiple fuse comprising an insulator core having a plurality of longitudinal 25 grooves therein, respective pin elements at each end, projecting into the grooves and having enlargements at their outer parts, fuses secured upon the pins in the grooves, the core having an insulator head at one 30 end having the enlargements of adjacent pins engaged therein, a relatively revoluble terminal member at the opposite end of the core electrically connected with all the adjacent pins, a terminal member revolubly 35 mounted on said head, and means to form electrical connection between the last named terminal member and adjacent pins alternately.

3. In a fuse, an insulator inclosure, an 40 elongated fuse therein having a central part of minimum resistance to fusion, means for making electrical connections with the ends of the fuse, said inclosure having a covering over the fuse having apertures spaced longitudinally over the fuse and an extremely 45 small fuse formed with a central part disposed over said covering surface and end portions projecting slidably through the said apertures into engagement with adjacent 50 end portions of the first named fuse, and a flexible covering over the second named fuse.

4. A multiple fuse comprising a core having a plurality of longitudinal grooves, a 55 revoluble terminal at one end having a plurality of pins electrically connected thereto and disposed in respective grooves, an insulator head at the opposite part of the core having pins therein projecting into the 60 grooves, fuses connecting the pins in each groove said pins in the head having contact portions countersunk in the exterior surface of the head, a terminal element mounted revolubly on the head and a contact thereon

positioned to successively engage the contact portions of the pins under relative rotation of the head.

5. As an improved article of manufacture, a terminal member for multiple fuses of the character described, formed of sheet 70 metal having a part adapted for connection with terminals in an electric circuit and a part constructed to form a bearing support for a rotating element, said last named part having an integral spring tongue formed 75 thereon and disposed to bear upon the rotating element when mounted on the support part.

6. A terminal for fuses of the character described comprising a contact portion, a 80 fuse mounting part extended therefrom apertured for a pivot element, a slit being formed therein concentric with the aperture, the outer material immediately beside the slit being inclined to bear upon a fuse 85 device mounted on the terminal for rotation concentric with said aperture.

7. In a device of the character described, a cased revoluble insulator core having longitudinal grooves therein stopping short 90 of the ends, pins inserted slidably in the ends of the core longitudinally into the grooves, the pins at one end being united upon a plate fixed against relative rotation upon the casing of the core, a terminal element having a revoluble connection with said plate, fuses in respective grooves of the core soldered to the ends of adjacent pins, a second terminal device revolubly 95 engaged with the appliance at the end opposite the first terminal device, and means to make electrical connections successively 100 with the adjacent pins under rotation of the core and casing.

8. A fuse device comprising two terminal 105 elements having parallel ear portions and a fuse casing revoluble therebetween, said casing having a plurality of fuse devices extended longitudinally therein all connected at one end to said terminal elements, a fuse 110 device including a core having a separate head portion at the opposite end from that above mentioned, a plurality of headed pins inserted through said head and the end of the core and attached to respective 115 fuses, a pivot bolt engaged through the head and having a retaining means at the inner side of the head, said bolt being engaged through the ear of the adjacent terminal member first mentioned.

120 9. In a multiple fuse device, a revoluble insulator core having a plurality of longitudinal grooves along the periphery thereof, but shorter than the length thereof, pins mounted in said insulator core beyond the 125 grooves and projecting into the ends thereof, a fuse in each of said grooves, each end of which is connected to the respective ends

of said pins, said pins at one end being connected to a revolubly mounted terminal, the pins at the other end being provided with enlargements, and means to selectively engage these enlargements as the core is turned on its axis.

In testimony whereof I have affixed my signature in presence of two witnesses.

HENRY J. GAGNON.
